BROOM MACHINE

Ernest C. C. Miller, Laurelton, N. Y.

Application February 19, 1947, Serial No. 729,467

1 Claim. (Cl. 242—7)

1

My invention relates to a broom-filling machine generally similar to that described in Patent No. 2,323,420 to Joseph S. Plumeau and myself, dated July 6, 1943.

Mechanical sweepers employed by municipalities in street-cleaning operations use rotary brooms which, although tough and rugged, are subject to such great wear as to necessitate frequent maintenance. The maintenance involves a complete rebuilding of the brooms. In municipalities in which large numbers of these sweepers are employed it frequently occurs that the brooms which must be maintained are of greatly differing dimensions. In particular, broom lengths vary, and these brooms are mounted upon supporting spindles of various sizes and configurations. Previous machines have been unable to accommodate the wide variety of broom types which must be serviced.

It is, accordingly, an object of my invention to provide an improved broom-filling machine of the character indicated.

It is another object to provide an improved broom-filling machine which will be adaptable to the quick and easy servicing of a variety of broom types and sizes.

It is a more specific object to provide a simple drive mechanism for a machine of the character indicated.

It is a further object to provide an improved broom machine wherein the shut-down time for the machine may be held to a minimum in applying a broom to or removing a broom from its journalled position on the machine—in other words, it is desired to keep the productivity of the machine at a high level regardless of the variety of types of brooms successively serviced.

Other objects and various further features of the invention will be pointed out or will occur to those skilled in the art from a reading of the following specification in conjunction with the accompanying drawings. In said drawings:

Fig. 1 is a partially broken-away front view of a machine incorporating features of my invention;

Fig. 2 is a right-hand side view of the machine of Fig. 1; and

Fig. 3 is an enlarged fragmentary view taken substantially in the plane 3—3 of Fig. 1.

Broadly speaking, my invention contemplates a broom machine comprising a frame in which a cable drum is revolvably supported at both ends, and in which a broom drum is revolvably supported at one end by the frame and at its other end by a longitudinally adjustable jour-

nalling means. Torques may be applied to rotate either the cable drum or a broom depending upon the operation that is to be performed. In the specific form to be described, the adjustable journaling means for the broom drum is 5 slidable in ways extending the full longitudinal length of the machine, and a broom drum once inserted on the machine is immediately engageable with the drive means. No brakes, adapters, or other fixtures need be applied or adjusted on a broom drum, once mounted upon the machine.

Referring to the drawings, my invention is shown in application to a machine having a frame comprising longitudinally extending base members 5, upstanding side members 6—7 at both ends, a top beam or brace 8, rearwardly extending base members 9, and trusses 10 to assure an erect and level assembly. A cable drum 11 extends the full longitudinal length of the machine and is 15 journalled at both ends in frame members 6 and 7. At one end the cable drum 11 is extended as at 12 so as to support driving means in the form of a worm wheel 13. At the same end of the machine, namely, in the upstanding frame member 7, 20 fixed journaling means 14 are provided for one end of a broom drum 15 to be accommodated and serviced on the machine.

In accordance with the invention, the other end of the broom drum 15 is supported in longitudinally adjustable journaling means 16. The journaling means 16 may be formed with or carried by a generally upright member 17 slidable in longitudinally extending ways. In the form shown, the upper end of the adjustable member 35 17 includes a bushing 18 surrounding and slidable along the cable drum, and the lower end is formed with a slide member 19 engaging tracks or ways 20 which may comprise a channel member secured at both ends to the upright frame members 6—7. The slide member 19 may include a 40 pair of arms 21—22 embracing both flanges of the channel 20 and a clamping hand screw member 23 for anchoring the adjustable member 17, for any particular length of broom to be serviced.

Drive means for the broom drum 15 may include 45 a worm wheel 24 journalled as at 25 in a built-out portion 26 of the frame of the machine. This drive means preferably also includes a dog member 27 for engagement with a corresponding dog or lug part 28 carried by the broom 15 to be serviced.

In accordance with another feature of the invention, worm means are employed to drive the worm wheels 13—24, and a simple manual adjustment is all that is needed for associating this

worm means with either of the worm wheels 13-24. In the form shown, the worm means comprises a shaft 29 supporting two spaced worms 30-31 which are preferably so positioned that either of these worms 30-31 is in engagement with one or the other of the worm wheels 13-24. The shaft 30 may be journalled at both ends in a cradle 32 which is preferably supported by the frame 7 for slight pivotal or rocking displacement about a transversely extending axis. In the form shown, the transverse support for the cradle 32 includes a bracket 33 secured to the frame member 7 and a stub shaft 34 in the bracket 33. Rotary power may be supplied to the worm shaft 29 through a fluid motor 35 carried at the lower end thereof and connected by a suitable arrangement of pipes 36 to an electrically driven pump 37 on the lower part on the frame of the machine. A treadle mechanism 38 at the front of the machine may be employed to operate a flow-control valve 39 for regulating the speed of drive by the motor 35. Selective engagement of the driving worms 30-31 with one of the worm wheels 13-24 may be effected through a manual crank 40, accessible from the front end of the machine and threadedly associated with a part 41 of the cradle 32.

The operation of my machine in filling a new broom is as follows. Before installation upon the machine, the broom 15 is fitted with a dog 28 of size appropriate for the spindle on that particular broom. Also before installation, the adjustable journalling means 16 is longitudinally positioned for the correct length of the new broom 15 as by sliding the top bushing 18 along the cable drum 11, and the lower slide 19 along the ways 28. Journal clamps 42-43 are released, and both the machine and the broom are ready for installation. Once the broom is mounted in the journals 14-16, the dog 28 and the dog 27 will engage one another, and final longitudinal adjustment of the journalling member 17 may be effected before clamping the same, as by turning the hand set 23. Journal clamps 42, 43 may then be set. If the broom is an old one to be resoled, a chain 44, secured at one end to the cable drum 11, is attached at the other end to the cable 45 (then wound on the worn brush). This cable 45 is first wound upon the cable drum 11, as by engaging the worm 30 with the worm wheel 31 and by applying a tautening brake 46 to the broom-drum drive means before stepping upon the treadle 38 to rotate the cable drum 11. When the cable 45 is completely wound upon the cable drum 11, the broom drum 15 is ready for refilling.

Refilling is accomplished in the manner indicated in the above-identified patent, while driving the broom drum directly. This direct drive may be effected quickly by a release of the broom-drum tautening brake 46, by an application of

cable-drum tautening brake 47, and by a simple turning of the crank 40 so as to mesh the worm 31 with the worm wheel 34. The completely filled broom may be finished-off by securing the chain-end of the cable 45 to the broom drum 15 (as by tacking or stapling the cable to the drum 15). The filled broom may then be removed after releasing the chain 44 from cable 45 and relaxing the journal clamps 42-43. The machine 10 will then be ready to accommodate the next broom. After removal from the servicing machine, the only operation necessary before installing the refilled broom in a street-sweeping machine is a simple removal of the adapter dog 15 28.

It will be appreciated that I have described a machine which lends itself readily to the efficient maintenance of a variety of broom types and sizes. The construction is such that shut-down 20 time for the machine during periods of adjustment and adaptation is held to an absolute minimum.

While I have described my invention in detail for the preferred form shown, it will be understood that modifications may be made within the 25 scope of the invention as defined in the claim which follows.

I claim:

In a machine of the character indicated, a cable 30 drum for winding a broom cable, broom-drum supporting means for a broom to be serviced, braking means for said cable drum and for a broom drum held in said supporting means, a worm wheel associated with said cable drum for 35 driving the same, a worm wheel for driving a broom drum held by said supporting means, a casing pivotally supported between said worm wheels for selective rocking toward one or the other of said worm wheels, worm means carried 40 by said casing for selective engagement with one of said worm wheels upon such rocking action, and a hydraulic motor for driving said worm means, said motor being carried by said casing, whereby rotary drive may be selectively applied 45 either to said cable drum or to a broom drum by a simple rocking operation of said casing.

ERNEST C. C. MILLER.
